US0D1112620S

(12) **United States Design Patent** (10) **Patent No.:** **US D1,112,620 S**
(45) **Date of Patent:** **** Feb. 10, 2026**

(54) **PUMP SPRAYER**

(71) Applicant: **Taizhou Luqiao Chengbo Qihua Plastic Co., Ltd.**, Taizhou (CN)

(72) Inventor: **Chaoqun Wang**, Taizhou (CN)

(**) Term: **15 Years**

(21) Appl. No.: **29/930,735**

(22) Filed: **Mar. 1, 2024**

(51) LOC (15) Cl. **23-01**

(52) U.S. Cl.

USPC **D23/225**

(58) **Field of Classification Search**

(57) **CLAIM**

The ornamental design for a pump sprayer, as shown and described.

DESCRIPTION

FIG. 1 is a front perspective view of a pump sprayer, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof; and,

FIG. 9 is an enlarged detail view of area 9 in FIG. 1. The long dash-short dash broken lines encircling the enlarged views are for annotative purposes only and form no part of the claim thereof.

1 Claim, 9 Drawing Sheets
